UNITED STATES PATENT OFFICE.

ALFRED P. MILLER, OF CHICAGO, ILLINOIS, ASSIGNOR TO THE MILLER CAR LOCK & SEAL COMPANY, OF SAME PLACE.

CAR-SEAL.

SPECIFICATION forming part of Letters Patent No. 679,979, dated August 6, 1901.

Application filed October 22, 1900. Serial No. 33,890. (No model.)

To all whom it may concern:

Be it known that I, ALFRED P. MILLER, a resident of Chicago, in the county of Cook and State of Illinois, have invented certain new and useful Improvements in Car-Seals, of which the following is a specification.

My invention relates to car-seals; and its object is to provide a simple and efficient seal made from a single strip and having a novel construction for fastening or sealing the ends together.

In the drawings, Figure 1 is a plan view of the blank, full size; Fig. 2, a similar view of a completed seal; Fig. 3, an edge view of the same; Fig. 4, an edge view of the strip sealed; Fig. 5, a section on line 5 5 of Fig. 6; Fig. 6, an enlarged view of one end of a seal, showing one face, Fig. 7 showing the other face; and Fig. 8, an enlarged perspective of the cup 20 end of the strip or blank.

As a convenient method of manufacture and as particularly well illustrating this invention the blank may be cut to form the strip 1, with the round ends 2 and 3. The 25 end 2 has a small hole 4, while the end 3 has a comparatively large hole 5. The end 3 is struck up so as to form a cup 6, whose diameter equals that of the end 2, which is intended to fit in such cup. On the end 2 is 30 formed an eyelet 7, which is made of a size to pass through the hole 5. This eyelet is preferably made slightly truncated, conical in form, so as to readily find the hole 5. As shown clearly in Figs. 1 and 2, similar triangular spaces 8 are cut out near the end 3, so that the cup may be formed continuous 35 except for a narrow opening 9, just wide enough to receive the narrow neck 10, immediately below the end 2 of the strip.

40 The strip being passed through the parts to be locked or sealed, the ends of the seal are brought together, with the end 2 resting in the cup 6 and its eyelet 7 passing through the hole 5. By a suitable double-acting press 45 the eyelet is now upset against the end 3, and the cup is folded over upon the end 2. The resulting seal is clearly shown in Figs. 4 to 7 of the drawings.

When the cup is formed, there result projecting points 11 at the opening 9. These points are advantageous not only because

they afford an extended binding-surface, as shown in Fig. 7, but also because they assure the proper inbending of the cup, inasmuch as the plunger of the press first strikes these points, which turn inward, the remainder of the cup following.

55 My seal is not only made in a single piece, but both of its ends are so made as to engage each other firmly against possibility of loosening or coming apart. In fact, the seal cannot be removed without breaking it.

60 So far as the feature of the cup is broadly concerned it will be understood that such cup may be used in connection with the eyelet feature or not, as may be desired, an efficient seal being provided by simply bending the cup over the end of the seal which is received within it.

65 It is evident that obvious changes may be made in the sizes and proportions of parts and that equivalent constructions may be adopted without departing from the spirit and scope of my invention and claims.

70 The end 3 of the strip after being struck up forms practically a cup-shaped portion, which in the absence of a better term I am pleased to call a "cup," although it may have a side opening and in the preferred form a bottom opening.

75 I claim—

1. A car-seal formed in a single piece and comprising a strip having at one end, and integral therewith, a cup to receive within it the other end of the strip over which such cup is folded down.

75 2. A car-seal comprising a strip having near one end a hole and also having a cup, the other end of the strip being provided with an eyelet, the said hole receiving such eyelet and the cup receiving within it such other end of the strip.

80 3. A car-seal comprising a strip having at one end a cup with a side opening 9 and having its other end formed so as to be received within the cup and provided with a neck 10 entering said opening, the cup being folded over upon the strip received within it.

85 4. A car-seal comprising a strip 1 having at one end a hole 5 and also a cup 6 with a side opening 9 and having at its other end 2 an eyelet 7 and a neck 10, the end 2 entering

within the cup and its eyelet passing through the hole 5 and its neck being received by said side opening in the cup, the seal being sealed by upsetting the eyelet and folding down the cup.

5. A car-seal comprising a strip having near one end a hole and also having a cup with projecting points 11, the other end of the strip having an eyelet, the said hole receiving such eyelet and the cup receiving within it the eyelet end of the strip.

6. A car-seal formed in a single piece and comprising a strip having at one end, and integral therewith, a cup, the other end of the strip being adapted to lie flat upon the first-named end of the strip and within the cup, the cup being adapted to be folded down upon the end of the strip so received within it.

ALFRED P. MILLER.
